CLOTH WINDING BOARD

Herbert H. Provence, Greenville, S. C.

Application March 15, 1933, Serial No. 660,970

4 Claims. (Cl. 206—50)

This invention relates to winding boards commonly used as cores and upon which bolts of cloth may be wound. The general object of this invention is to provide a winding board which 5 may be very cheaply made of laminated fabric such as laminated pasteboard or the equivalent thereof and yet which is rigid and which is reinforced across each end to strengthen the ends of the board against crushing and bending and 10 for the further purpose of thickening the ends of the board or core so as to permit the attachment of labels thereto and provide a relatively large space at the ends of the board for the attachment and presentation of said labels.

15 A further object is to provide a winding board of this character in which the board toward its ends is gradually increased in thickness so as to prevent material wound on the board from being creased or wrinkled and a still further object 20 is to provide a board so constructed as to permit the use of a light weight material for the body and so constructed that there is no need for the machine operator to be particular about which side of the board is placed on the winder frame 25 since both sides are alike, thus saving much time in winding the cloth.

Other objects will appear in the course of the following description.

My invention is illustrated in the accompanying drawing, wherein:

Figure 1 is a perspective view of a board constructed in accordance with my invention;

Figure 2 is a longitudinal section on the line 2—2 of Figure 1;

Figure 3 is a fragmentary transverse section on the line 3—3 of Figure 1;

Figure 4 is a fragmentary sectional view of one end of a board showing a slightly modified construction.

As shown particularly well in Figure 2, the body of the board comprises a web 10 of light weight material such as more or less stiff and rigid pasteboard, the pasteboard being laminated or not as may be found best and having a thickness at its middle of approximately one-eighth of an inch. As before remarked, the body portion of the board may be of laminated material or solid material as desired. This stock or web 10 may be formed, for instance, of two sheets of 45 pasteboard glued together along their entire extent and then the two sheets are split or separated at their ends and disposed between these split ends or separated ends is a transversely extending reinforcing strip 11 which may also be of 50 laminated stock or may be of solid, relatively

thick stock. The two thicknesses of the web 10 and the intermediate strip 11 at each end of the board are then stapled to each other by staples 12 or otherwise intimately connected to each other. I do not wish to be limited to the use of 55 staples as other means might be used for holding the strips in place in the ends of the boards.

As before remarked, the web 10 will have, under ordinary conditions, a thickness of approximately one-eighth of an inch while the ends of the board 60 in actual practice will have an average thickness of five-sixteenths of an inch so that a relatively wide label designated 13 may be applied to one or both ends of the board, or to embrace the end.

It is to be particularly noted that there is a 65 gradual slope from the ends of the board inward for approximately two inches and that then the board is flat across its entire length until it reaches the opposite end of the board. Because of this gradual slope from the thick ends inward 70 toward the middle of the board, cloth wrapped upon this board will not tear or wrinkle. Where a reinforcing strip is applied to the exterior face or faces of a winding board, there is a great liability of the cloth being wrinkled and sometimes 75 such boards tear the cloth badly. With my board, the cloth may be wound to the extremities of the board so that the extremities of the board are flush with the ends of the bolt without any liability of the material being wrinkled or torn.

The construction of my board permits the use 80 of a light weight material for the body, yet the ends are sufficiently strong and thick to hold the cloth properly and to show up to advantage the printed labels 13 often used on the ends. Light 85 boards are less costly than boards having a thickness equal to the ends of my boards, they reduce the cost of transportation because of their lightness and they give a finished appearance to the bolt of cloth equaling that of cloth wound on 90 heavy boards.

In actual use, these boards are ordinarily about 95 eighteen inches long and are used to wind cloth approximately thirty-five inches wide. The cloth is doubled which makes the actual width as wound 100 on the board seventeen and one-half inches. Strictly speaking, therefore, the cloth would hardly reach to the extreme thickened ends of the board and would be wound around the middle portion of the board. In actual practice, however, the cloth does not wind absolutely true and because of the stretch, weaves from side to side 105 slightly. Thus it actually covers the entire board including the reinforced ends but the full thickness of the cloth is not at both ends because the 110

entire thickness of the bolt does not cover the ends, there is no noticeable difference in either the thickness of the bolt or the smoothness because of the slight increase in the end thickness but with these gradually thickened ends, there is no tendency for the cloth to slide off, that is, slide inward. Where reinforcements in the form of strips are disposed upon the outside faces of the ends of the board and particularly where reinforcing strips are placed only on one side of the board at the ends thereof, there is a tendency for the cloth to slide off of the reinforcing strips, causing wrinkling in the middle portion of the cloth. This trouble is not experienced with my board because of the gradual sloping surface on each face of the board inward from the extreme thickness of the ends of the board to the inner middle portion of the web.

One of the distinctive advantages of this construction also resides in the fact that there is no need of the machine operator being particular about which side of the board is placed on the winder frame since both sides are alike. This saves time in winding the cloth, whereas if reinforcing strips are placed on the board on one side, the operator must take care that the board is properly placed in the winder frame.

While I do not wish to be limited to any particular manner of forming this board, yet preferably it is made of even plies, as for instance, two plies or four plies, so that there will be a joint of glue at the middle of the thickness of the board. Each end of the board is then split after the board has been cut to the desired size and the reinforcing strips 11, which may be of pulp board, wood, pasteboard or other material are then inserted in the split ends, these strips 11 being of any desired thickness depending upon the thickness which is wanted for the ends of the completed board. These strips 11 are then stapled, glued or otherwise fastened in, serving the double purpose of reinforcing the end of the board against bending, and making the end of the board thick enough for the label to be properly supported and look well. The labels might be attached at the same time that the strips 11 are inserted. The insertion of the strips 11 act to spread the plies of board on each side to form a sloping surface from the thick end to the thinner center.

It is to be understood that the board or web 10 is what may be termed a solid board, the ends being split inward for a short distance and the reinforcing members 11 inserted in the split ends. If it were possible to secure a piece of pulp board of sufficient thickness and made in one solid piece, the extremities of this solid board would be split and the reinforcing members inserted. It is not practical, however, for paper mills to make a solid board in one piece and, therefore, thinner boards are taken glued together in layers, and under great pressure, and in this way form the equivalent of a solid board. It is this laminated board which is practically solid which is illustrated in Figure 2. It is often the case that these laminated boards are slightly split at the ends, thus making it easy to separate these ends and insert the reinforcing members 11, but this is not at all necessary as I have used boards containing an uneven number of layers and split the center layer for inserting the strips 11.

The cloth wound upon this board goes approximately to the ends but due to the fact that there is a certain amount of stretch in the cloth, the slight slope from the thick ends to the thin middle

portion does not give any trouble when winding either as regards wrinkling or bulging. It will be noticed, however, that this sloping portion of the board is very short with reference to the entire length of the board which is shown most fully in Figure 1. If these slopes extended further inward toward the center of the board to or nearly to the middle of the board, there would be trouble in winding the cloth. It is to be noted, therefore, that by far the greater portion of the board is absolutely flat and of even thickness and that only at the end is there a gradual thickening of the board from a thickness of one-eighth of an inch to a thickness of approximately five-sixteenths of an inch and the upper and lower surfaces of the board extend to the ends without any shoulders, breaks, or other solution of continuity. This can only be achieved by splitting a board or thin web at the ends and inserting the strips 11.

I do not wish to be limited to the idea of splitting the ends of the board and inserting the strips 11 as it is entirely possible to make the board initially with gradually thickened ends as shown in Figure 4 where a board is illustrated in which the ends 11a are thickened and made out of solid stock. Neither do I wish to be limited to the particular form for the strips 11 as these may be uniformly cross-sectional or somewhat wedge-shaped, if desired.

What is claimed is:—

1. A cloth winding board comprising a web of relatively thin material formed of an equal number of plies on each side of the median plane of the web, the end portions of the web being split along this median plane, reinforcing strips inserted in this split whereby to increase the thickness of the web at its extremities, and means rigidly holding the strips and the plies on each of the strips integrally connected.

2. A cloth winding board comprising a web of thin material and of even thickness as regards its middle portion from a point adjacent one end of the board to a point adjacent the other end, the extreme ends of the web being split and narrow strips inserted in said split ends, the outer edges of the strips and the outer edges of the split portions of the board terminating in approximately the same plane, the upper and lower surfaces of the board from end to end being continuously curved outward from the middle toward the ends without break of continuity.

3. A cloth winding board comprising a web of thin material, the web having a uniform thickness from a point adjacent one end to a point adjacent the other end, the ends of the web being split, and narrow reinforcing strips inserted in said split ends, the split ends and the strips being rigidly engaged with each other, the board thus having thickened relatively narrow end portions gradually merging into the middle portion of the board without break in continuity of surface.

4. A cloth winding board comprising a web of relatively thin longitudinally laminated material, the end portions of the web being split along the lines of one of said laminations, narrow reinforcing strips inserted in these splits, and means rigidly holding the strips and the plies on each side of the strips integrally connected, the board having a relatively long body portion of uniform thickness gradually merging into outwardly inclined end portions without break in continuity of surface.
